UNITED STATES PATENT OFFICE

107,958

DESIGN FOR A STRAINER

Clarence R. T. Hess, Prairie View, Ill., assignor to Edward Katzinger Company, Chicago, Ill.,
a corporation of Illinois

Application January 13, 1937, Serial No. 67,027

Term of patent 3½ years

To all whom it may concern:

Be it known that I, Clarence R. T. Hess, a citizen of the United States, residing at Prairie View, in the county of Lake and State of Illinois, have invented a new, original, and ornamental Design for a Strainer, of which the following is a specification, reference being had to the accompanying drawing, forming part thereof.

Fig. 1 is a side elevational view of the strainer showing my design; and

Fig. 2 is a top plan view thereof.

The shading on the exterior wall and handle of the strainer represents contrasting colors.

I claim:

The ornamental design for a strainer, as shown and described.

CLARENCE R. T. HESS.
